his Atty.

UNITED STATES PATENT OFFICE.

CHARLES W. E. CLARKE, OF NEW YORK, N. Y.

PULVERIZED FUEL COMBUSTION SYSTEM.

Application filed November 10, 1923. Serial No. 673,920.

This invention relates to apparatus for burning powdered fuels, hereinafter for convenience referred to as "coal". The advantages of burning coal in a powdered or

designate the elements just referred to. All the parts so far described are constructed, arranged, and operate in a well known manner.

60

5 pulverized condition have commanded themselves so strongly to steam power plant engineers, that this type of combustion system is going into use very rapidly. Such systems, however, requires a preliminary treatment of the coal at the plant in which it is to be burned, and the present invention is concerned particularly with this preliminary treatment or preparation of the coal.

According to the present invention, a green coal bunker 12 is located above the furnace and at a higher level than the powdered fuel bunker 6.

65

10 The crushed green coal is delivered to this bunker 12 by any suitable conveying or elevating mechanism, as, for instance, by a belt conveyor, bucket conveyor, or the like, the upper end of such a conveyor being indicated at 14. In the arrangement shown, the elements of the 70

treatment or preparing apparatus are arranged in duplicate. These elements comprise two dryers 15 and 15' into which the coal feeds by gravity directly from the bottom of the bunker 12. These dryers are ar-

75

15 ranged to be heated by waste heat or flue gases from the furnace, and for this purpose a wind trunk or conduit 16 leads gases from the stack 5 to the dryer 15, while another trunk or conduit 17 conducts these 80

gases from the drier to the intake end of a blower 18 which forces them through an ex- 85

20 haust pipe 19 back into the stack 5. The circulation of gases through the dryer of course is created by the blower. Corresponding connections, indicated by primed numerals, are provided for the opposite 90

25 dryer 15'. These dryers may be of a known type, consisting of alternate coal and air spaces separated from each other so that the 95 coal is spread out in relatively thin streams as it passes through the dryer.

30 The nature of the invention will be readily understood from the following description when read in connection with the accompanying drawings, and the novel features will be particularly pointed out in the appended claims.

35 From the dryers 15 and 15' the coal passes directly by gravity into pulverizers 20 and 20', respectively. The coal in the pulverizer 95

40 20 is next run through a pneumatic separator, commonly called a cyclone separator. That is, it is picked up in a current of air created by the blower 21 and forced into a separator 22. From this separator the coal 100

45 drops by gravity either directly into a pulverized coal bunker 6, or else into distributing screw conveyors 24 which deliver it to the pulverized fuel bins or bunkers.

50 It will now be evident that this arrangement requires but a single handling of the coal, the green coal being delivered directly to a green coal bunker which is so located that gravity is utilized thereafter to deliver the coal from one treating unit to the next. 110

55 Not only is the handling of the coal, therefore, made more economical, but the initial

cost of the treating or preparation plant is substantially reduced since the expense of a separate building structure for this plant is avoided. That is, the preparation plant be heated by flue gases from said furnace, utilized the walls, columns, and foundations of the power plant itself. Further advantages of this arrangement are that it reduces the floor space required for the preparation plant, and it permits the drying of the green coal by waste flue gases from the boiler furnaces.

While I have herein shown and described a preferred embodiment of my invention, it will be understood that the arrangement of the elements of the treating plant necessarily will depend to some extent upon the design, location and arrangement of the power plant with which the treating apparatus is to be used, and also with the nature of the treatment or preparation which the fuel is to undergo. The invention therefore may be embodied in many forms without departing from the spirit or scope thereof.

Having thus described my invention, what I desire to claim as new is:

1. In a powdered fuel combustion system, the combination of a furnace, a green coal bunker mounted above said furnace, means for feeding coal to the furnace, and coal treating apparatus located between said feeding means and said bunker, said apparatus including a pulverizer into which the coal is fed by gravity from said bunker.
2. In a powdered fuel combustion system, the combination of a furnace, a pulverized fuel bunker, means for feeding coal from said bunker to the furnace, a green coal bunker located above the level of said powdered fuel bunker, and coal treating apparatus through which the coal is fed from said green coal bunker to said pulverized fuel bunker, said apparatus including treating units to which the coal is fed by gravity from said green coal bunker.
3. In a powdered fuel combustion system, the combination of a furnace, a pulverized fuel bunker, means for feeding coal from said bunker to the furnace, a green coal bunker located above the level of said
4. In a powdered fuel combustion system, the combination of a furnace, a green coal bunker located above said furnace, an elevator for delivering coal to said bunker, a drier into which said green coal is arranged to be fed by gravity from said bunker, said drier being arranged to be heated by flue gases from said furnace, a pulverizer into which the coal flows by gravity from said drier, a pneumatic separator through which the coal is passed from said pulverizer, and means for utilizing gravity in conducting the coal from said separator to said pulverized coal bunker.
5. In a powdered fuel combustion system, the combination of a furnace, a green coal bunker mounted above said furnace, means for feeding coal to the furnace, and coal treating apparatus located between said feeding means and said bunker, said apparatus including a drier into which the coal is fed by gravity from said bunker and a pulverizer into which the coal passes by gravity from said drier.
6. In a powdered fuel combustion system, the combination of a furnace, a green coal bunker located above said furnace, means for delivering coal to said bunker, a drier into which said green coal is arranged to be fed by gravity from said bunker, a pulverizer into which the coal flows by gravity from said drier, a pneumatic separator through which the coal is discharged from said pulverizer, a pulverized fuel bunker located below said separator and into which the coal is discharged from the separator by gravity, and means for conducting coal from said pulverized fuel bunker to said furnace.
7. In a powdered fuel combustion system, the combination of a furnace, a green coal bunker mounted above said furnace, means for feeding coal to the furnace, and coal treating apparatus located between said feeding means and said bunker, said apparatus including a drier into which the coal is fed by gravity from said bunker and a pulverizer into which the coal passes by gravity from said drier.
8. In a powdered fuel combustion system, the combination of a furnace, a green coal bunker located above said furnace, means for delivering coal to said bunker, a drier into which said green coal is arranged to be fed by gravity from said bunker, a pulverizer into which the coal flows by gravity from said drier, a pneumatic separator through which the coal is discharged from said pulverizer, a pulverized fuel bunker located below said separator and into which the coal is discharged from the separator by gravity, and means for conducting coal from said pulverized fuel bunker to said furnace.

CHARLES W. E. CLARKE.
